UNITED STATES PATENT OFFICE.

GEORGE A. DEMO, OF NEWPORT, MINNESOTA.

WINDOW-SHADE FASTENING.

No. 818,359.

Specification of Letters Patent.

Patented April 17, 1906.

Application filed November 7, 1905. Serial No. 286,240.

To all whom it may concern:

Be it known that I, GEORGE A. DEMO, a citizen of the United States of America, residing at Newport, in the county of Washington, ton and State of Minnesota, have invented new and useful Improvements in Window-Shade Fastenings, of which the following is a specification.

This invention relates to an improved means for fastening curtain-shades to shade-rollers, the object of the invention being to provide simple and effective means whereby the shade may be securely fastened to the roller in such manner as to be readily and conveniently removed when desired, and whereby the use of tacks and other similar fastenings which mutilate the roller and insecurely attach the shade thereto is obviated.

The preferred embodiment of the invention is illustrated in the accompanying drawings, in which—

Figure 1 is a view in elevation of a shade-roller and a portion of the shade attached thereto by my improved fastening means, a portion of the shade being broken away to show one of the fastening members. Fig. 2 is a cross-section, on an enlarged scale, taken on the line 2 2 of Fig. 1. Fig. 3 is an inner face view of the extended band-strip with a clasp applied thereto. Fig. 4 is an outer face view of the same, showing the clasp extended. Fig. 5 is a view similar to Fig. 4, showing the clasp in folded condition for use. Fig. 6 is a detail view of one of the eyelets. Fig. 7 is a section, on an enlarged scale, taken on the plane indicated by the line 7 7 of Fig. 1.

Referring now more particularly to the drawings, the numeral 1 designates a window-shade, and 2 its supporting-roller, which may be made of any suitable materials and, if desired, conform to those in general use.

In accordance with my invention, the end of the shade to be attached to the roller is provided at suitable intervals with metallic eyelets 3, while the roller is provided with a coöperating series of attaching devices. Each of these attaching devices consists of a metallic strip 4, bent to form a band to closely embrace the roller with sufficient friction to hold it from movement thereon. This strip has its end portions bent or folded

upon itself in opposite directions to form hooked terminals 5 and 6, which are adapted to interlock in the manner shown in Fig. 2 to hold the strip in band form and permit of its ready application to and removal from the roller when occasion requires.

The band carries a fastening device formed of a thin strip of metal bent centrally to provide a looped body portion 7 to embrace the band-strip and having its ends normally projecting at right angles to said looped portion to form bendable clasp-fingers 8. The construction of these parts is clearly shown in Fig. 7, which illustrates the fingers inserted through an eyelet in the shade in the first stage of securing the shade to the roller. After the eyelet has been fitted upon the fingers the latter are bent laterally in opposite directions against the outer side of the shade to hold the same in applied position.

Any desired number of the eyelets and fastening devices may be employed, according to the length of the roller and width of the shade and the weight of the latter, to firmly fasten the same to the roller, and it will be seen that the construction is such that the fastening devices may be employed upon any type of shade-roller in common use and that the shade may be repeatedly applied and removed without injury thereto or to the roller.

The fastening devices are, it is apparent, simple in construction and may be manufactured and sold at a comparatively low cost.

Having thus described the invention, what is claimed as new is—

1. The combination with a shade-roller, and a shade provided with eyelets, of bands embracing the roller and having their ends interlocked to hold them from circumferential movement thereon, and a clasp carried by each band, said clasps having looped portions embracing the bands and bendable fingers passing through said eyelets and clenched against the outer face of the shade. 95

2. The combination with a shade-roller and a shade provided with eyelets, of bands closely embracing the roller and having their ends interlocked to retain them in fixed position thereon, and clasps carried by the bands, said clasps having looped portions embracing the bands above the shoulders formed by 100

the interlocking ends thereof in the direction of revolution of the roller, and provided with bendable fingers passing through the eyelets in the shade and clenched against the outer 5 face of the latter, the interlocking ends of the bands thus serving to hold the clasp from shifting under the resistance of the shade.

In testimony whereof I affix my signature in presence of two witnesses.

GEORGE A. DEMO.
